UNITED STATES PATENT OFFICE.

GUSS F. SPOONER, OF CHICAGO, ILLINOIS.

SCREEN.

1,285,448.

Specification of Letters Patent. Patented Nov. 19, 1918.

Application filed March 28, 1918. Serial No. 225,320.

To all whom it may concern:

Be it known that I, GUSS F. SPOONER, a citizen of the United States, residing at Chicago, in the county of Cook and State of Illinois, have invented certain new and useful Improvements in Screens, of which the following is a specification.

My invention pertains to various features of novelty and advantage in improved forms 10 of screens or sieves adapted to economically and efficiently separate solids or semi-solids from a liquid, such, for example, as to divide out or disunite the particles of matter from the liquids of garbage reduction plants.

15 The invention is not limited or restricted to any particular use or line of industry, but it lends itself especially favorably to employments wherein the solid particles have a tendency to adhere to the screens, and accordingly one important feature of the present invention is an improved and effective 20 means for cleaning the screens, it being understood that the appliance has a plurality of such screens or drains which come into 25 operation successively and act or function more or less conjointly.

A simple and convenient embodiment of the invention comprises a suitable framework supporting an endless carrier or conveyor to which a plurality of overlapping hinged screens or sieves are attached. Co-acting with these is a presser-roller which squeezes or presses the solid material on the screens to express the entrapped liquid 35 therefrom, thus rendering such material of a more compact and condensed nature. Such pressure or squeezing action causes these more or less solid particles to adhere or cling to the screens and to clog their interstices or 40 apertures. To automatically clean the screens they are permitted to drop in sequence against a fixed or rigid abutment, whereby the sudden stopping of their fall and the jar given them shakes off the adhering matter, leaving the screens comparatively clean.

The various instrumentalities employed in effecting such cleaning, in expressing the liquid, and in preventing the screens from 45 becoming interlocked by swinging into contact with one another constitute the prime or leading features or characteristics of the invention. Its principal object and salient purpose is the provision of an appliance of this general character which is in structure, simple, in operation, effective and efficient,

and in the cost of production and operation, economical.

To enable those skilled in this art to understand and appreciate the invention from a structural as well as a functional standpoint, I have illustrated a desirable embodiment of the same in the accompanying drawings forming a part of this specification and throughout the various views of which like reference characters refer to the same parts.

In these drawings:

Figure 1 is a plan view of the structure;

Fig. 2 is a substantially-central, longitudinal, vertical section through the same;

Fig. 3 illustrates on an enlarged scale and in section the means employed for swinging these screens on their pivots preliminary to their falling;

Fig. 4 shows the same parts in a different position; and

Fig. 5 is a detail view of the screen revolving or overturning mechanism and the means for preventing the screens from improperly contacting with one another.

The appliance includes any suitable or desirable framework 20 provided with supporting legs or posts, (not shown) and on this framework or table, near its opposite ends, two parallel shafts 21 and 22 are mounted for rotation in pairs of bearings 23, 23, and 24, 24, the latter being adjustable lengthwise the frame or table by screw means 25, 25, for taking out the slack in the conveyer about to be described. A pair of sprocket-wheels 26, 26, are mounted on and fixed to shaft 21 in spaced relation and in like manner shaft 22 is fitted with a pair of alined sprocket-wheels 27, 27. Cooperating with and taking around these pairs of wheels are two parallel sprocket-chains 28, 28, cross-connected together at intervals by hingebars 29, 29, by which the front edges of the several screens or sieves 30, 30, are hinged to the chains at suitable intervals.

Each of such screens or reticulated or perforated members is slightly tapered rearwardly and at its opposite ends or edges has marginal upstanding perforated or open-work walls or flanges 31, 31, the screens overlapping or interfitting slightly as illustrated, the wider, front, end portion of each receiving the slightly-narrower, rear, end portion of the next one ahead of it.

At the upper stretch or length of such chains and mounted in any approved manner lengthwise on the framework are a pair

of round rods 32, 32, on which grooved rollers 33, 33, revoluble on the hinge-rods between the screens and chains, travel to properly support the chains and prevent the screens from sagging. Also on the framework adjacent to the lower lengths or stretches of the chains are similar rods 33^a on which the same rollers travel in the opposite direction. The appliance is driven by means of a sprocket-wheel or pulley 34 secured to a protruding end of shaft 21, although any desirable driving means may be substituted.

The liquid, containing more or less suspended or contained solid matter, is delivered or poured on to the overlapped screens from a spout 35, shown in full lines in Fig. 2 and in dotted lines in Fig. 1. Near one end of the apparatus I provide a pressure-roller 36 mounted on a cross-shaft 37 above the screens and revoluble in bearings in a super-frame 38, such roller being desirably provided with a resilient covering or facing 39, such for example, as burlap, which permits a ready conformation of the surface of the roller to the material passing beneath it, the roller having associated with it a spring-pressed scraper bar or plate 40. Beneath the roller, below the screens, a supplemental supporting-roller 41 is employed to hold the screens up in place and prevent undue distortion or bending.

At one end the frame is equipped with a suitably-supported, adjustable, abutment-bar 50 of a length, crosswise the apparatus, slightly less than the length of the shorter longitudinal edge of one of the screens. In passing around one end of the frame, that is, at one end of the endless conveyer, the screens fall in succession on to this stop-bar which suddenly and temporarily arrests their descent, shaking or jarring off all adhering matter. Then as the chains continue the travel of the screen or sieve the latter is drawn off of the abutment, swings down, and hangs vertically suspended from the sprocket-chains in traversing the space below the lower stretch of the chains.

I provide special means to swing the screens over and cause their sudden fall on to the abutment, and also means for preventing the screens upon leaving the abutment from swinging into contact with their suspended neighboring screens. If the screens are allowed to rock or swing into contact with one another, they are likely, owing to their tapered construction and the more or less rough nature of the screens themselves, to become interlocked, which prevents their laying out flat when traversing the upper part of the appliance. Accordingly, shaft 22 has a two-armed pushing or overturning member 60 fastened to it, the free or outer ends of the arms being bent rearwardly at 61, to each of which ends a

bar 62 is pivoted at 63 to a bracket 64, each bar having a flat extension bar 65 slidingly secured to it by a slot and pin connection 66. This screen swinging or overthrowing appliance performs two functions. It positively engages each clogged screen as it arrives in position above it and overturns it at a definite point in its travel, assuring that all screens will fall and strike the abutment in the same manner and secure practically the same jar or jolt for each, and it acts additionally as a safety appliance in that it prevents any of the screens from traveling too far with the conveyer before falling and thus possibly not striking the stop-bar. Its second operation is to prevent the screens from swinging into contact with one another after dropping off of the abutment.

As is shown in Fig. 2, as each screen approaches the end of the conveyer, one of the arms 60 comes up beneath it and begins to turn it upwardly around its forwardly-traveling hinge-bar 29. When such hinge-bar has reached the position illustrated in Fig. 3, its screen will have been swung by the pusher, lifter, or overthrowing arm into vertical position and immediately it falls over and strikes abutment 50, from which it gradually recedes until it is about to drop off, as shown in Fig. 4.

When the screen frees itself from the shelf or abutment, it falls or swings down into the dotted line position of Fig. 4, striking the end of bar 65 of the other arm of part 60, which prevents it from coming into contact with the next screen ahead of it. At this time bar 62 is in contact and supported by the end of the bent section 61 and the extension-bar 65 is projected its full limit both of which conditions have been brought about automatically by the action of gravity on the structural elements concerned. At this point the inclination of the companion bars 62 and 65 is such that the screens hitting the end of the latter cannot push it upwardly out of position, so that the bar acts temporarily as an effective stop against the detrimental or excessive swinging referred to. As the lower arm 60 in Fig. 4 continues traveling upwardly, bar 62 and its companion bar 65 hung thereon swing on the pivot or hinge of the former into the relation shown in Figs. 2 and 3, which permits the arm 60 to raise its screen without having the parts 62 and 65 conflict with or strike the next screen or its hinge-bar. As the rotation of shaft 22 proceeds, such upper arm 60, when reaching the position of the lower arm 60 in Fig. 2, has its bars 62 and 65 folded or compacted as shown, that is to say, bar 65 has slid down due to gravity so that its extension beyond bar 62 is a minimum, and it rests on the hub of arm 60. Then upon further rotation of the shaft this contracted arm swings down

125

130

around its hinge-pin into the position shown in the lower part of Fig. 3. Owing to the fact that during this swinging the arms 62 and 65 are contracted or telescoped the latter escapes engagement with the screen just above it. But, as has been indicated above, before it is necessary for such bar 65 to become active as a stop it slides down by gravity into the relation illustrated in Fig. 4.

The liquid draining through the traveling screens or sieves is received in a tank or trough 70 from which it flows out through a discharge pipe or passage 71. The solid matter retained on the screens and jarred loose therefrom may be received in any form of suitable receptacle, not shown.

The operation of the appliance occurs substantially as follows:

The liquid, containing more or less solid matter in suspension, flows from the spout 35 on to the overlapped screens or sieves over which it naturally spreads out, most of the liquid draining through into the receptacle 70. The contained solid matter cannot flow with it over the edges of the screens at the sides of the machine because of the recirculated flanges. When such solid matter reaches the roller 36 it is squeezed or pressed thereby, and any excess material which will not readily pass under the roller is held back by it until the thickness of the material is reduced sufficiently to permit such passage. Thus, some of such solid matter may be held back by the roller and caused to pass from one screen to the next. Undesired lateral expression of the matter is prevented by the rims or flanges on the screens. The resilient or elastic facing on the roller permits its surface to conform more or less readily to the material passing beneath it and to press somewhat into the holes or interstices of the screens. Roller 41 is in the nature of a rolling support to hold the screens up to the work, preventing undue sagging or deflection. Each screen or sieve, as it reaches the end of the apparatus, is positively lifted and caused to fall and strike the abutment, thus cleaning it and discharging all adhering matter. Later the screen leaves the abutment and falls therefrom, being prevented from swinging into engagement with the next screen by the means fully illustrated and described above. As these screens come up at the other end of the mechanism, they align themselves in overlapped relation, unitedly or conjointly forming a moving screen of substantial capacity.

To those skilled in this art the attainment of the desired objects specified in the mechanism described will be readily understood, but it is also to be appreciated that the invention is not limited and restricted to the precise and exact structural features

presented because many minor mechanical changes may be made in the apparatus without the sacrifice of any of its substantial benefits and advantages and without departure from the substance and heart of the invention. For example, in the drawings I have shown the roller 36 of sufficient weight to adequately perform its squeezing function, but if desired, such roller may be supplemented by spring means to augment its pressure against the screens and their contents.

I claim:

1. In an appliance of the character described, the combination of an endless-conveyer, a plurality of screens mounted on said conveyer, a roller overlying such screens and adapted to squeeze the material resting thereon, and means to jar said screens in succession after passing said roller to free them from adhering matter, substantially as described. 85

2. In an appliance of the character described, the combination of an endless-conveyer, a plurality of screens mounted on said conveyer, means to squeeze the material resting on said screens, and means to jar said screens in succession after passing said squeezing means to free them from adhering matter, substantially as described. 90

3. In an appliance of the character described, the combination of an endless-conveyer, a plurality of screens mounted on said conveyer and adapted to overlap one another during at least a portion of their travel, a roller overlying such overlapped screens and adapted to squeeze the material resting thereon, and means to jar said screens in succession after passing said roller to free them from adhering matter, substantially as described. 95

4. In an appliance of the character described, the combination of an endless-conveyer, a plurality of screens mounted on said conveyer and adapted to overlap one another during at least a portion of their travel, means to squeeze the material resting on said screens, and means to jar said screens in succession after passing said squeezing means to free them from adhering matter, substantially as described. 110

5. In an appliance of the character described, the combination of an endless-conveyer, a plurality of screens hinged to said conveyer and adapted to overlap one another during at least a portion of their travel, a roller overlying said overlapped screens and adapted to squeeze the material resting thereon, and an abutment adapted to be struck by said hinged screens as they fall during change in their direction of travel at one end of the endless-conveyer, whereby to free the screens from adhering matter, substantially as described. 125

6. In an appliance of the character described, the combination of an endless-con- 130

1. In an appliance of the character described, the combination of a pair of shafts, an endless-conveyer mounted on said shafts, a plurality of screens hinged to said conveyer, an abutment adapted to be struck by the screens in succession to jar them free from adhering matter, and means on one of said shafts and supplemental to said conveyer to swing said screens in succession about their hinge connections with the conveyer preliminary to their striking said abutment, substantially as described. 65
2. In an appliance of the character described, the combination of an endless-conveyer, a plurality of screens mounted on said conveyer and adapted to overlap one another during at least a portion of their travel, said screens having upstanding end flanges also adapted to overlap one another, a roller overlying such overlapped screens and adapted to squeeze the material resting thereon, and means to jar said screens in succession after passing such roller to free them from adhering matter, substantially as described. 70
3. In an appliance of the character described, the combination of an endless-conveyer, a plurality of screens hinged to said conveyer, an abutment adapted to be struck by said hinged screens as they change their direction of travel at one end of the endless-conveyer, whereby to jar the screens free from adhering matter, and means to prevent the screens depending from said conveyer from swinging into contact with one another, substantially as described. 75
4. In an appliance of the character described, the combination of an endless-conveyer, a plurality of screens hinged to said conveyer and adapted to overlap one another during at least a portion of their travel, a roller overlying said overlapped screens and adapted to squeeze the material resting thereon, an abutment adapted to be struck by said hinged screens as they fall during their change of direction of travel at one end of the endless-conveyer, whereby to jar the screens free from adhering matter, and means to prevent the screens depending from said conveyer after leaving said abutment from swinging into contact with one another, substantially as described. 80
5. In an appliance of the character described, the combination of an endless-conveyer, a plurality of screens hinged to said conveyer, an abutment adapted to be struck by the screens to jar them free from adhering matter, and means supplemental to said conveyer to swing said screens in succession about their hinge connections with the conveyer preliminary to their striking said abutment, substantially as described. 85
6. In an appliance of the character described, the combination of an endless-conveyer, a plurality of screens hinged to said conveyer, an abutment against which said screens are adapted to fall, and automatically expanding and contracting means to prevent the screens upon leaving said abutment from swinging into contact with an adjacent screen, substantially as described. 90
7. In an appliance of the character described, the combination of an endless-conveyer, a plurality of screens hinged to said conveyer, an abutment against which said screens are adapted to fall, and automatically expanding and contracting means to prevent the screens upon leaving said abutment from swinging into contact with an adjacent screen, including a hinged member and a second member slidable thereon, substantially as described. 95
8. In an appliance of the character described, the combination of an endless-conveyer, a plurality of screens hinged to said conveyer, an abutment against which said screens are adapted to fall, a rotary arm adapted to overturn said screens, and automatically expanding and contracting means on said arm to prevent the screens upon leaving said abutment from swinging into contact with an adjacent screen, including a bar hinged to the end of said arm, and a second bar slidable on said hinged bar, substantially as described. 100
9. In an appliance of the character described, the combination of an endless-conveyer, a plurality of screens hinged to said conveyer, an abutment against which said screens are adapted to fall jarring them free from adhering matter, means supplemental to said conveyer to turn said screens in succession about their hinged connections with the conveyer preliminary to their striking said abutment, and means mounted on said turning means to prevent the screens upon leaving said abutment from swinging into contact with an adjacent screen, substantially as described. 105

GUSS F. SPOONER.
